SELF-PERFORATING INK CONTAINER

Edgar Gene Shelton, Ponca City, Okla.

Application April 11, 1946, Serial No. 661,409

1 Claim. (Cl. 120—45.4)

1

The invention relates to a writing instrument and more particularly to an ink cartridge writing pen.

The primary object of the invention is the provision of a pen of this character, wherein the ink cartridge for supplying ink to the point is detachably mounted so that there will be no leakage of ink during the feeding period and the cartridge is punctured in a novel and unique manner for the flow of ink to the writing point of the pen.

Another object of the invention is the provision of a pen of this character, wherein the nipple for the point has fitted detachably therein a puncturing element, which on the fitting of the ink cartridge to this nipple will perforate the said cartridge so that ink flow will be established in the pen for writing purposes, the puncturing element being of novel construction and unique in its mounting within the pen.

A further object of the invention is the provision of a pen of this character, wherein the cartridge is fitted within the same so as to assure against leakage during the use of the said pen, the cartridge after the emptying of the same of its content can be thrown away and a new cartridge substituted.

A still further object of the invention is the provision of a pen of this character, which is simple in construction, thoroughly reliable and efficient in operation, strong, durable, neat in appearance, readily and easily operated to effect the flow of the ink from the cartridge to the point of the pen, and inexpensive to manufacture.

With these and other objects in view the invention consists in the features of construction, combination and arrangement of parts as will be hereinafter more fully described, illustrated in the accompanying drawing, which discloses the preferred and modified forms of construction of the invention and pointed out in the claim hereunto appended.

In the accompanying drawing:

Figure 1 is a fragmentary sectional view through a pen constructed in accordance with the invention.

Figure 2 is a view similar to Figure 1 showing a slight modification of ink cartridge and fittings.

Figure 3 is a vertical longitudinal sectional view the punch member for the pen shown in Figure 1.

Figure 4 is an end view of the member.

Similar reference characters indicate corresponding parts throughout the several views in the drawing.

2

Referring to the drawing in detail, particularly Figure 1, the pen constituting the present invention, comprises a cylindrical shell forming a part of the barrel body 10 of the said pen, having at one end the usual nipple 11 which has in its opening 12 a feed plug 13 for the fitting therein of the writing quill 14 which is generally termed the pen point.

The barrel body 10 and the opening 12 in the nipple 11 are separated by a dividing web 15 in this instance, having a centrally located threaded clearance or vacancy for accommodating a punching nozzle 16, which is detachably screwed into the threaded clearance or vacancy and has a longitudinal bore 17 leading to the opening 12 at its outer end and through a longitudinally slotted tapered punch tip 18. This tip protrudes through a cupped elastic sealing washer 19, which is seated in the barrel body 10 against the web 15 and about the said tip 18.

Adapted to be telescopically fitted to the barrel body 10, is an ink cartridge 20 having a thinned thrust end 21 which on pressing against the tip 18 becomes fractured or punctured, so that ink 25 of the cartridge can freely flow through the bore 17 into the opening 12 and the plug 13, whence such ink is delivered to the quill or point 14. The end 21 of the cartridge 20 will seat in the washer 19, where it becomes sealed about the tip 18 to 30 avoid leakage of ink at this point. The cartridge 20 is frictionally held in the barrel body 10 for confinement therein in any suitable manner.

In Figure 2 of the drawing, there is shown a slight modification of the pen, wherein the cartridge is formed with a reduced externally threaded puncturing end 23, and which is designed to be punched by the punch member 24, which is of less length than the member 16, yet operates in an identical manner. The cartridge at the end 40 23 is screwed into a coupling sleeve 25 fixed in the barrel body 26, and this cartridge creates a continuation of the latter.

What is claimed is:

In a fountain pen of the refilling ink tube cartridge type, the combination which comprises a substantially hollow barrel forming a handle and having a nipple integral therewith and extended from the writing end thereof, said barrel having a transversely disposed web dividing the opening in the lower end of the barrel from the nipple, and said web having a centrally disposed threaded bore therethrough, and an ink tube punching nozzle having a threaded base positioned in the said threaded bore of the web and 55 having an extended conical shaped inner end

with transversely disposed slits therethrough extended into the adjoining end of the barrel and positioned to puncture an ink tube in the barrel, said nozzle having a longitudinally disposed ink carrying channel therethrough, and a cup shaped elastic sealing washer in the lower end of the barrel and through which the said conical shape inner end of the nozzle extends with a portion of the base thereto threaded in said sealing washer.

10 EDGAR GENE SHELTON.
